UNITED STATES PATENT OFFICE.

FREDERICK CARDER, OF CORNING, NEW YORK, ASSIGNOR TO CORNING GLASS WORKS, OF CORNING, NEW YORK, A CORPORATION OF NEW YORK.

DESIGN FOR A PITCHER.

Application filed August 22, 1922. Serial No. 3,509. Term of patent 14 years.

To all whom it may concern:

Be it known that I, FREDERICK CARDER, a citizen of the United States, residing at Corning, in the county of Steuben, State of New York, have invented a new, original, and ornamental Design for Pitcher, of which the following is a specification, reference being had to the accompanying drawing, forming ing part thereof, in which the figure is a side elevation of a pitcher showing my new design.

I claim:—

The ornamental design for a pitcher, as shown.

FREDERICK CARDER.
